UNITED STATES PATENT OFFICE.

WILLIAM H. PIKE, JR., OF SOUTH ORANGE, NEW JERSEY, ASSIGNOR TO PIKE ADDING MACHINE COMPANY, OF ORANGE, NEW JERSEY, A CORPORATION OF NEW JERSEY.

ADDING-MACHINE.

No. 922,627.

Specification of Letters Patent. Patented May 25, 1909.

Application filed May 24, 1906. Serial No. 318,510.

To all whom it may concern:

Be it known that I, WILLIAM H. PIKE, Jr., a citizen of the United States, residing at South Orange, in the county of Essex and State of New Jersey, have invented certain new and useful Improvements in Adding-Machines, of which the following is a specification.

In those classes of adding machines in which type carriers are moved in one direction by springs to extents determined by the keys depressed, it is necessary to employ springs of such strength as will insure the necessary rapid action, and in quick acting machines, as those driven by motors, these springs must be correspondingly heavier. This results in the tendency of the springs to overthrow parts of the operating mechanism, in loading the machine with an undue degree of resistance in setting the parts connected to extend the springs, and results in the tendency of the parts to rebound after reaching proper position so that it is necessary to employ brake or friction devices to overcome the overthrow and rebound tendencies. Such devices, of course, increase the working load and require an increase of driving power, over what would otherwise be needed.

To overcome these objections I make use of two sets of springs with means whereby one set is active only during part of the operations, and so arrange the cam, when the latter is used to operate the carriers, as to prevent overthrow, as fully set forth hereinafter and as illustrated in the accompanying drawing, in which,

Figure 1 is a sectional elevation of sufficient of an adding machine to illustrate one manner in which my improvement may be employed; Fig. 2, a similar view showing the parts in a different position; Fig. 3 is a plan of Fig. 2.

While my invention may be employed in connection with machines of different constructions, I have illustrated it in connection with the parts of such a machine as is shown in Letters Patent No. 763,692, granted to me June 28, 1904. As in said machine, there are type carriers 403 which, as shown, are in the form of levers, and with each carrier is connected a rack strip 404, and springs 404^a connected with these rack strips tend to carry the parts so as to bring stops 430 upon the strips against the stems of such keys 201 as may be depressed, the extent of movement

depending upon the key depressed, and a corresponding type of each type lever being thereby brought over the platen 880 into printing position. With the type carriers is combined a suitable device for shifting the same to normal position prior to each printing operation. As shown, the said device consists of a plate 401 constituting part of a swinging frame J, which, when carried toward and with the type carriers, will set them all to normal position. As one means of operating the device or frame J, there is shown a cam 900, and a roller bearing 402 of the frame is held in contact with the cam in one direction by the action of the springs 404^a in the construction shown, so that as the cam is lifted to its upper position, the said springs will carry the levers to the printing positions determined by the extent of movement permitted by the keys and stops.

In carrying out my improvement the cam 900 is constructed so as to act positively to carry the device or frame J in a direction away from the levers as well as toward them, and for this purpose is provided with a slot 80 for receiving the friction roll 492, and this will prevent any rebounding of the frame or levers however rapidly the machine may be operated.

Instead of depending upon the springs 404^a alone to hold the type carriers against the operating device 401 or, whatever it may be, I connect the operating device and each type lever by a spring connection, as for instance, by a spring a, so arranged that it tends to hold the levers and the operating device in close connection, and in the absence of any interference, the two will swing together under the action of the cam or other operating part. When the frame J is swung backward, as the cam descends in carrying the type carriers to normal position, only the springs 404^a are put under stress, but when the cam is raised the frame J will swing toward the cam and all of the type carriers capable of movement will swing forward with the frame, unless the parts are operated with such rapidity that the frame is swung away from these levers, in which case the springs a will be extended or put under stress so that the joint action of the two springs is thrown upon each lever to operate the same and insure its desired rapid movement. In other words, the stress of both the springs 404^a and a may be thrown upon each type carrier whenever re-

quired to insure the desired rapid action, after the operation of the machine begins in adding while in restoring the parts to normal position it is only necessary to overcome the 5 resistance of the springs 404*. It will of course be understood that this applies only to the operations in connection with such type carriers as are actually moved during a printing operation, for it will be seen that as 10 to those carriers which remain in position the springs *a* thereof will be extended as the frame J swings forward. While this, to a certain extent, adds to the load in operating the machine, it will be seen that this load 15 comes only upon a part of the carriers, that is, upon such as are not moved at any one adding operation, and this is in part compensated for by the fact that on the return movement the springs that have been extended or 20 put under the extra stress, tend to swing the frame J in the position to restore the other parts and put stress and counteract upon the springs 404*. By thus making use of two sets of springs I am, therefore, able to secure 25 the effect on each of the rack strips 404 of both springs without necessarily actually expanding or putting under additional stress the springs *a* which tend to hold the carriers and swinging frame or other operating device 30 in juxtaposition, so that I secure sufficient strength of spring or, energy of spring action, to operate the parts with the desired rapidity, and that I secure this result without unduly loading the machine. It will further be 35 seen, that by the use of a cam which acts positively to control the movement of the type carriers to printing position, I prevent any overthrow of the parts. It will be seen, therefore, that the brake devices heretofore 40 required to prevent overthrow or rebound may be dispensed with, or greatly reduced in energy, and the operation of the apparatus correspondingly facilitated.

Without limiting myself to the precise construction and arrangement of parts shown, I claim:

1. The combination with the type carriers of an adding machine, of springs connected to shift the type carriers to printing position, 50 a device for shifting the carriers to normal position and a second set of springs, arranged and connected to be put under stress tending to shift the type carriers when the said device is carried in a direction from the latter.

55 2. The combination with the type carriers, and stops for defining the movements of the type carriers of an adding machine, of springs to shift the carriers to positions limited by the stops, other springs for acting in the same 60 direction, and means adjustable to put the latter springs under stress to aid in shifting the carriers.

3. The combination with the type carriers of an adding machine, of two sets of 65 springs to act on the said carriers to carry

them to printing position, one set normally under stress to effect said result, and means whereby the other set may be put under stress after the movement of the carriers begins.

70 4. The combination with the type carriers of an adding machine, of two sets of springs, one normally under constant stress to move said carriers, and means whereby when the machine is operated in adding the other 75 springs may be put under stress.

5. The combination with the type carriers of an adding machine, of springs connected to carry the carriers to printing position, means for carrying the carriers to normal position, and springs connecting said means and carriers and arranged to be put under stress only as said means is carried from the carriers.

80 6. The combination in an adding machine of the type carriers and means for defining the movements of such carriers, of springs whereby the type carriers are shifted to positions determined by said means, and other springs, and means whereby the latter may 90 be put under stress to supplement the action of the first-named springs as the type carriers begin their movements in one direction.

7. The combination with the type carriers, of an adding machine and means for 95 determining the movements of the type carriers, of springs connected to carry the type carriers to positions determined by such means, a device for shifting the carriers to printing position, a cam, and a second set of 100 springs and means whereby the latter may be put under stress as the cam is shifted to shift the position of said devices in respect to the carriers, substantially as set forth.

8. The combination with the type carriers, and means for determining the movements thereof in an adding machine, of 105 springs for shifting the carriers to printing positions, a swinging frame, means for operating the frame to move the carriers to normal positions, and spring connections between the frame and carriers.

9. The combination with the type carriers, and means for determining the movements thereof, of springs for shifting the carriers to printing positions, a swinging frame, means for operating the frame to move the carriers to normal positions, spring connections between the frame and carriers, and a cam for positively operating the frame.

110 10. The combination with the type carriers, and means for determining the movements thereof, of a spring for shifting each carrier to printing position, a reciprocating device for shifting the carriers to normal positions, and a spring connection between each carrier and said device arranged to be put under stress when the device is moved from the carrier.

115 11. The combination with the type car-

riers, and the means for determining the movements thereof, and springs for carrying the type carriers to printing position, of a swinging frame and means for operating the same, and a spring connection between the frame and each carrier arranged to be put under stress as the frame leaves the carrier.

12. The combination with the type carriers, and means for determining the movements thereof and springs for carrying the type carriers to printing position, of a swinging frame and a cam for operating the same, and a spring connection between the frame and each carrier arranged to be put under stress as the frame leaves the carrier.

13. The combination with the type carriers, stops, numeral keys and springs for shifting the carriers to printing position, of a swinging frame and a cam arranged to act positively in both directions to swing the frame with and from the carriers, and a spring connection between said frame and each carrier.

14. The combination with the type carriers and swinging frame, of a cam for operating the frame positively in both directions to carry it in a direction from the carriers, and a spring connection between each carrier and the frame.

15. The combination with the type carriers of an adding machine, of two sets of springs arranged and connected to shift the carriers to printing position, a shifter for shifting the carriers to non-printing position, and connections between the shifter and one set of springs whereby the latter are relaxed as the shifter is operated to set the carriers to non-printing position and which are put under stress when the shifter is moved from the carriers.

In testimony whereof I affix my signature in presence of two witnesses.
